UNITED STATES PATENT OFFICE

WILLIAM BANGSER, OF NEW YORK, N. Y., ASSIGNOR TO H. MAIMIN COMPANY, INCORPORATED, A CORPORATION OF NEW YORK

CLOTH-CUTTING MACHINE

Application filed September 28, 1929. Serial No. 395,897.

This invention relates to cloth-cutting machines of the reciprocating knife type, and particularly to means for mounting the cross-head through which the knife is reciprocated.

5 Two types of cloth-cutting machines are in common use, the rotary knife type and the reciprocating knife type. The merits of the former are that as long as the knife is rotating and the machine is moved forward 10 through the lay the knife is cutting. It is therefore a more efficient type of cutter than the reciprocating knife type in which only the down stroke is the effective cutting stroke. On the other hand, the rotary knife cannot 15 be used on relatively thick lays, nor can it be used in cutting very intricate patterns. For such use the reciprocating knife type cutter must be employed.

In a cloth-cutting machine of the reciprocating knife type the cutting knife is mounted for vertical reciprocation within an upright standard. The upper end of the knife is fixed to a cross-head which is reciprocated in suitable gibs by means of a pitman connected to 25 a crank disc mounted upon the shaft of an electric motor. In machines of this type in use today the cross-head makes a sliding metal to metal contact with the gibs. Now, for most efficient cutting an extremely rapid 30 rate of reciprocation is required, the motors of the present high speed machines operating at about 3600 R. P. M. Compared with the machines of the rotary knife type, it is necessary that machines of the reciprocating type 35 develop greater power. This is because of the greater thickness of the lays cut, and also because of the sharp corners which it is necessary to turn with these machines. For this reason there is a constant pressure 40 brought to bear on manufacturers of cloth-cutting machines to build more powerful machines. This might be done by increasing the motor size, but it is practically impossible to do this because of the physical limitations 45 of the machine. It is awkward for an operator to handle a machine upon which a very large and powerful motor is mounted.

In order to permit the development of speeds as high as 3600 R. P. M. when using 50 the sliding cross-head of the present day ma-

chine, it is necessary that the cross-head and gib be lubricated continually. At least once an hour the operator must see to it that these parts are well lubricated; if he fails in this the cross-head will bind and actually stop the 55 machine. It is evident, therefore, that the cross-head and its mounting constitute an inefficient link in the power chain, and consume power in overcoming friction which might be applied to better advantage in cutting cloth. 60

Another objection to the present type of cross-head and gibs arises from the frequent lubrication required. Even though the operator exercises the utmost care some of the 65 oil escapes at the lower end of the gibs and creeps down the standard, ultimately coming in contact with the goods. When working on fine fabrics, such as silks, this is very 70 objectionable and may result in ruining, if not seriously damaging, the material being cut.

It is, therefore, the object of the present invention to provide a reciprocating cross-head with its gibs or guideways so constructed as 75 to avoid or minimize the disadvantages discussed above. I have attained this object by interposing bearing balls between the cross-head and the gibs so that instead of a sliding metal to metal contact, I have a rolling metal 80 to metal contact which reduces friction to the minimum and enables me to obtain a substantial increase in power without increasing the size or design of the motor. Such a rolling contact also permits the development 85 of much higher speeds. I can, without difficulty, employ a motor designed to rotate at 4000 R. P. M. and even higher.

By the use of my improved cross-head construction lubrication difficulties are practically eliminated. Instead of lubricating every hour it is necessary only that small quantities of grease be applied not oftener than once a week and probably not that 90 often. The grease, too, does not run down the gibs and soil the cloth being cut, so that I not only obtain a superior lubrication, requiring considerable less attention, but I also, at the same time, overcome a difficulty which 95 100

has always been a problem to those using cloth-cutting machines of the reciprocating knife type.

Although it would be possible to employ balls making contact with only one of the relatively moving members, I prefer to construct the cross-head and gibs so that the balls roll on each. Each ball, therefore, moves only one-half the stroke of the cross-head. Thus, it is necessary for me to employ a row of balls substantially one-half only the length of the cross-head. The use of more than this number would be objectionable, because then the end balls, at least during part 15 of the stroke, would be sliding and not rolling.

In the accompanying drawings I have illustrated a preferred embodiment of my invention, a study of which will make the principles involved clear. In these drawings Figure 1 is an end view of a cloth-cutting machine of the reciprocating knife type constructed in accordance with the present invention with the front cover plate and presser foot removed to expose the cross-head and gibs; Figure 2 is a longitudinal section taken along line 2—2 of Figure 1 showing the front plate and presser foot in position; Figure 3 is an enlarged transverse section taken along line 3—3 of Figure 1; Figure 4 is a similar transverse section taken along line 4—4 of Figure 1; Figure 5 is a vertical section taken along line 5—5 of Figure 3; Figure 6 is a view similar to Figure 5, but showing a modified construction, and Figure 7 is a transverse section taken along line 7—7 of Figure 6.

The cloth-cutting machine illustrated in these drawings comprises a base 1 from which arises a standard 2, supporting a motor housing 3, a motor 4, and a handle 5. The standard 2 and the housing 3 constitute a support for the other parts of the machine. Slidably mounted within a slotted recess in the standard 2 is the cutting knife 6 which is reciprocated by means of the motor through connections which will be described in detail presently. The front of the motor housing 3 is enclosed by means of a plate 8 which carries an adjustable presser foot 9.

The upper end of the knife 6 is bolted to a lug 11 depending from and integral with a cross-head 12. Projecting outwardly from the center of the front face of the cross-head and integral therewith is a boss 13 which serves as a wrist pin. In order to assist in keeping the parts cool and to lighten the reciprocating member, I preferably drill a hole 14 through the wrist pin boss and cross-head, as illustrated most clearly in Figure 3. The lower end of a pitman 15 is pivotally mounted on the wrist pin 13 by means of a ball bearing 16. The upper end of this pitman is fixed to a crank pin 17 journalled within a

ball bearing 18 in a crank disc 19 carried by the forward end of the motor shaft 20 journalled by means of ball bearing 21 in the motor frame. The motor, acting through crank disc 19, pitman 15 and cross-head 12, reciprocates the knife.

In machines of this type now in common use the cross-head makes sliding engagement with a pair of vertical gibs. In the machine of the present invention the cross-head moves vertically between a pair of gibs 23, but does not make actual contact with them. Interposed between the cross-head and the gibs are two series of balls 24, one on either side of the cross-head. I shall now describe the manner in which these balls are mounted with particular reference to Figures 3 and 5.

The cross-head is provided with a pair of vertical V-shaped grooves 25, one on either side, these grooves corresponding with and facing similar grooves 26 in the gibs. These two pairs of opposing grooves constitute races for the balls. The grooves 26 in the gibs may be open at their ends; the grooves in the cross-head, however, are closed, at their lower ends by means of projections 28 on the cross-head, and at their upper ends by means of a removable plate 29; projections 28 and plate 29 serving as stops limiting the movement of the balls. It will be noted from an inspection of Figure 5 that five balls are employed in each race and that the total overall length of these balls, when tangent, is only slightly greater than one-half the length of the cross-head. It will also be noted that the cross-head is substantially one-half the length of the gibs. The important feature, however, is the relation between the length of the space through which the balls can freely roll and the length of the cross-head stroke. Thus the throw of the crank disc is such that the stroke of the cross-head is not more than twice the distance between the center of the uppermost ball and the plate 29, as illustrated in Figure 5, with the cross-head in its uppermost position. As a result of this arrangement the balls are moved in rolling relation to both the cross-head and the gibs, each ball moving just one-half the stroke of the cross-head and at neither end of the stroke are these balls, or any of them, slid with reference to the gibs.

In order to supply the necessary small amount of grease to lubricate the balls and their races, I have mounted grease cups 31 on either side of the supporting frame. Each of these grease cups is provided with the usual screw threaded plunger having at its outer end a knurled wheel 32 by the turning of which grease is extruded through the nozzle of the cup. The nozzles of these cups register with opening 33 extending through the middle of the gibs, thus permitting the introduction of grease to the races.

In order to take up wear, one of the gibs is

mounted for lateral adjustment upon pins 34 and moved inward, when occasion arises, by means of setscrews 35.

In Figures 6 and 7 I have illustrated a slightly modified construction. Here the balls, instead of rolling freely in the races, are held in fixed relation to one another by means of a cage 37. By means of this construction the insertion and removal of the balls from the races is facilitated, but the principles involved are, of course, the same.

By means of the improved cross-head and the gib construction of the present invention I am enabled to do away with the old sliding cross-head and its attendant disadvantages. The rolling contact between the cross-head and its gibs materially reduces friction, enables the use of higher speed motors and permits the effective application of greater power with the same motor. In addition to these advantages I have reduced lubricating difficulties practically to a vanishing point which not only saves the time of the operator, but, in addition, eliminates the necessity for oil and makes it practically impossible for lubricant to come in contact with the fabrics being cut.

When reference is made in this specification and claims to balls I intend, of course, to include rollers and other equivalent anti-friction elements.

I claim:

1. In a cloth-cutting machine, the combination of a knife, a reciprocating cross-head connected thereto, gibs between which the cross-head moves and balls interposed between the cross-head and gib, said balls each being arranged to roll upon the cross-head and gib during reciprocation of the cross-head.

2. In a cloth-cutting machine of the reciprocating knife type, the combination of a knife, a cross-head connected thereto, gibs between which the cross-head moves, opposing grooves in the cross-head and gibs forming races, and balls in the races, the balls being so positioned with reference to the cross-head and its stroke that they are always in rolling relation to the cross-head and gib.

3. In a cloth-cutting machine of the reciprocating knife type, the combination of a knife, a cross-head connected thereto, gibs between which the cross-head moves, opposing grooves in the cross-head and gibs forming races, stops at the ends of the grooves in the cross-head, and balls in the races occupying a part only of the space between the stops enabling the balls to roll relative to the races as the cross-head is reciprocated.

4. In a cloth-cutting machine of the reciprocating knife type, the combination of a knife, a cross-head connected thereto, gibs between which the cross-head moves, opposing grooves in the cross-head and gibs forming races, stops at the ends of the grooves in

the cross-head, and balls in the races occupying a part only of the space between the stops, the empty space between the stops being substantially half the stroke of the cross-head.

In testimony whereof I affix my signature.

WILLIAM BANGSER.
